UNITED STATES PATENT OFFICE.

ENRICO BATTISTI, OF ROME, ITALY.

FASTENING DEVICE FOR WEARING-APPAREL.

1,129,624.

Specification of Letters Patent. Patented Feb. 23, 1915.

Application filed September 7, 1912. Serial No. 719,259.

To all whom it may concern:

Be it known that I, ENRICO BATTISTI, of Rome, in the Kingdom of Italy, have invented certain new and useful Improvements in Fastening Devices for Wearing-Apparel, of which the following is a specification, reference being had to the accompanying drawing, forming part thereof.

The object of the present invention is a fastening device for temporarily joining together the edges of dress articles such as shoes, leggings, gloves, corsets, and the like, in substitution of buttons, laces, buckles, eyelet-holes, clasps, &c., as well as the ends of wrappers for parcels and the like, thus doing away with stitches and seals.

The device is formed of three parts, namely of two side pieces applied to the borders of the ends to be joined together, the said pieces being equal and disposed symmetrically like two ribbons with the borders facing themselves turned outward with respect to the joining line, that is to say each border turned toward the edge, to which is applied the piece, and of the third intermediate or locking piece, which is also shaped like a ribbon with the borders turned inward. In order to establish the connection, this middle piece is pushed into the two approached side pieces in such a way that its borders turned inward slide beneath the outward turned borders of the side pieces, joining them together.

In the annexed drawings: Figure 1 shows a portion of the ribbon constituting either one of the two side pieces, or the middle piece, before bending one of its borders, or both, the said ribbon having been strengthened by means of a continuous wire strand; Fig. 1^a is similar to Fig. 1, but the ribbon is strengthened by means of a wire chain; Fig. 2 shows a front view of one of the two side pieces, one of its borders being bent; Fig. 3 shows a front view of the middle piece both of its borders being bent; Fig. 4 shows the entire device, partially locked and in operation; Figs. 5, 6, 7 and 8 are respectively cross-sections on lines 5—5 of Fig. 1^a; 6—6 of Fig. 2; 7—7 of Fig. 3 and 8—8 of Fig. 4.

As shown in the drawings, the two side

pieces have the shape of a ribbon —a—, the border —b— of which is turned outward so as to form a groove, and the middle piece —c— is also shaped like a ribbon, but both of the borders —d— of which are turned inward. The side pieces are sewed, stitched or otherwise secured to the borders of the ends to be joined together, so that their outward turned corners —b— face each other. In this way, when the ends are sufficiently approached, the inward turned borders —d— of the middle piece may be caused to slide within the groove formed by the outward turned borders —b— of the side pieces. The flexibility necessary to easily fit the said pieces to the different shapes of the edges to be joined together is obtained by forming each of the three pieces with a web of zigzagged wire passing from one border to the other on the whole width of the ribbon, and to prevent the wire from yielding and stretching, in the middle portion is applied a suitable connecting means, such as a continuous wire strand *l. t.* (Fig. 1), or a chain *l. a.* (Fig. 1^a) with ring-shaped links, in order to keep together the successive zigzagged segments.

In the drawing the ribbon is shown as formed by a hand provided with cuts so as to form the said zigzagged segments, but the ribbon may also be formed from a simple, successively bent wire.

When the device is applied to an article, of which the borders to be joined are already permanently united at one of their ends, as is the case with a shoe, then the middle piece may be provided with a spring button —e— (Figs. 3 and 4) having the well-known shape which at the end of the stroke of the middle piece joins in the known manner with a resilient crown fastened to the shoe.

Having now fully described this my invention and how the same is to be carried out, I declare that what I claim is:

In a device for joining together the edges of clothes and the like, comprising two side pieces having a border turned outward so as to form a groove, and a third piece having both of the borders turned inward, in order to connect the latter with the former

ones, causing it to shove with its bent borders into the grooves of the side pieces, the said three pieces being formed by a wire replicately zigzagged from one border to the
5 other, in order to form a plain metallic web, and suitable means connecting the zigzagged segments on the middle line of the web.

In testimony, that I claim the foregoing as my invention, I have signed my name in presence of two subscribing witnesses.

ENRICO BATTISTI.
